ENGINE-STARTER.

1,125,130.

Specification of Letters Patent. Patented Jan. 19, 1915.

Application filed May 1, 1914. Serial No. 835,686.

To all whom it may concern:

Be it known that we, JOHN L. LAKE, a subject of the King of Great Britain and a citizen of the Dominion of Canada, and 5 GEORGE WILLIAM BEYERLE, a citizen of the United States, both residing at Cleveland, in the county of Cuyahoga and State of Ohio, have invented a certain new and useful Improvement in Engine-Starters, of which the 10 following is a full, clear, and exact description, reference being had to the accompanying drawings.

This invention relates to that class of mechanisms, known as engine starters, which 15 are used for imparting initial rotation to the crank shafts of internal combustion engines for the purpose of compressing a charge of gas in the cylinder of the engine, prior to igniting the same.

20 Our invention has for its general object to provide a mechanism of the above character which is simple of construction; easy of operation; and which is very durable.

To those familiar with the action of 25 internal combustion engines, it is well known that, incident to the starting of the engine, should the spark control be wrongly adjusted, the engine "back-fires", which means that the charge of gas is ignited and the 30 explosion takes place before the piston has reached the upper end of its stroke. This results in the crank shaft being given a violent turn in the reverse direction to that given it by the starting mechanism, and unless some means is provided for disconnecting 35 the mechanism from the shaft under such conditions, the mechanism is liable to damage and the operator to injury.

It is a further and very important object 40 of our invention, therefore, to provide means for automatically freeing the starting mechanism from the crank shaft of the engine, when the crank shaft is rotated in the direction opposite to that imparted to it by 45 said mechanism.

While we do not confine the use of our 50 invention to any particular type or size of internal combustion engines, it is especially adapted for use with the engines of motorcycles, and we have shown it in such connection in the accompanying draw-

ing, it being deemed advisable, for purpose of clearness, to include only such parts of the motorcycle, in the drawing, as will serve to show the manner of supporting the starting mechanism and its relation to the engine. 55

In the drawing, Figure 1 represents a plan view of the mechanism, said figure including a portion of the motorcycle frame and a part of the crank case of the engine; Fig. 2 is a central vertical section on the line 2—2 of Fig. 1; Fig. 3 is a section taken on the line a—a of Fig. 2 and looking in the direction of the arrows 3; Fig. 4 is a section on the same line a—a of Fig. 2 and looking in the direction of the arrows 4; while Fig. 5 is a sectional detail on the line 5—5 of Fig. 4. 60 65

Throughout the following description, 70 similar reference characters will be used to designate corresponding parts in the several views of the drawing.

Protruding from the crank case 1 of the engine is the end of the crank shaft 2, the 75 same being provided with a collar 3 just inside of the crank case. The extreme outer end of the crank shaft is threaded for the reception of a circular nut 4, which has notches 5 for the application of a suitable 80 wrench. Clamped between the inner face of the nut 4 and the opposed surface of the collar 3 is the inner end of a cylindrical coupler-member 6, said member having a central bore, a portion whereof, adjacent its 85 inner end, is of a size to fit the end of the shaft 2, while the opposite end of the bore is of greater diameter than said former portion, whereby a shoulder 7 is formed, against which abuts the inner end of the nut 4. The 90 outer end of the coupler-member 6 is provided with a lateral flange 8 that is connected, by the bolts 9, to the flange 10 of the coupler-member 11 which is secured, in any suitable manner, to the shaft 12. A key 95 13 locks the coupler-member 6 against rotation upon the shaft 2.

A clutch-member 14 is secured to the coupler-member 6, adjacent the crank case 1, by a pair of cap screws 15 which pass 100 through the clutch-member and are threaded into the member 6. Loosely mounted

upon the coupler-member 6 is a driving clutch member 16, and the opposed faces of the clutch members 14 and 16 are provided with ratchet teeth 17 and 18, respectively, the inclination of the teeth 17 and 18 being such as will cause the member 14 to be driven by the member 16 when the clutch faces of the members are in engagement and the clutch member 16 is rotated in the direction indicated by the arrows in Figs. 1 and 3, which is the running direction of rotation of the engine.

For descriptive purposes, it will be assumed that the shaft 2 projects from the rear side of the crank case, and, therefore, the end of the mechanism adjacent the crank case will be referred to as the front end. To the rear of its clutch face, the clutch member 16 is provided with a circumferential, angle gear 19; and still to the rear of the gear 19, the member is provided with a laterally projecting lug 21 having an inclined face 22, as shown very clearly in Figs. 4 and 5. Extending from diametrically opposite points of the flange 8, toward the rear end of the clutch member 16, are a pair of sleeves 23, which contain plungers 24 that are pressed against said clutch member by springs 25. These springs are comparatively light and, under certain conditions which will be explained hereinafter, tend to move the clutch member 16 toward the clutch member 14.

It will be stated at this time, that when our invention is used in connection with motorcycles, it is very convenient, and therefore preferable, to operate it by foot, although we wish to be understood as not limiting ourselves to such a method of actuating the mechanism, as it will become obvious as this description proceeds, that other means might be just as well employed for such purpose.

26 represents a member of the motorcycle frame that is located to one side of the crank case, and extends in a direction that is parallel to the shafts 2 and 12, and is in about the same horizontal plane. While we have shown but one frame member 26, it will be understood that a corresponding member is located on the opposite side of the crank case at the same distance from its center as the one shown in the drawing; and connecting the two side members is a transverse frame member 27 that is curved downwardly underneath the shaft 12, as shown in Figs. 1, 2, and 4.

Projecting inwardly and then downwardly from the frame member 26, in transverse alinement with the clutch member 16, is a bracket 28 which comprises a body portion that is secured to the frame member 26, and end plates 29, which carry, at their lower ends, a bolt 30, that is secured within the bracket by a nut 31. Journaled upon the

bolt 30 between the end plates 29, is the hub 32 of an angle gear segment 33 which meshes with the angle gear 19 of the clutch member 16. A spring 34, which is coiled about one end of the hub 32, has one of its ends anchored in one of the end plates 29, and its opposite end attached to a pin 35 which projects from one side of one of the spokes 36 of the segment 33. Projecting outwardly from the hub 32 beneath the frame member 26 and then upwardly, is an arm 37, the same being provided, at its upper end, with a suitable foot tread 38. Directly beneath the frame member 26, the arm is enlarged to form a vertically disposed, hollow, cylindrical boss 39, and within this boss is contained a rubber plug or bumper 40, for coöperation with the underneath side of the frame member 26, the aforesaid spring 34 being turned about the hub 32 in such a direction as will cause the segment to be thrown downward and the arm 37 upward to cause the plug 40 to contact with the underneath side of the frame member 26.

Projecting forwardly from the transverse frame member 27, directly beneath the rear end of the clutch member 16, is a bracket 41, which carries a block 42 that is locked within its forward, bifurcated end, by a bolt 43. A projection 44 rises from the block and has an inclined face 45 for coöperation with the inclined face 22 of the lug 21 that extends laterally from the rear end of the clutch member 16. The purpose of these coöperating parts will be brought out in the description of the operation of the mechanism which follows.

When it is desired to start the engine, the operator places his foot upon the tread 38 of the arm 37 and presses said arm downwardly against the tension of the spring 34, rocking the segment 33 and thereby rotating the clutch member 16 through approximately 270°. The inclination of the teeth of the gear 19 and the teeth of the segment 33 is such as will cause the clutch member 16 to be slid forwardly on the coupler member 6 and into engagement with the clutch member 14. In fact, before the clutch member 16 has been rotated any appreciable distance, it will have been advanced into engagement with the clutch member 14, the longitudinal movement of the clutch member 16 being partially effected by the spring pressed plungers 24. Now, therefore, it will be seen that when the arm 37 has been pushed downwardly, the clutch member 16 will have been thrown into engagement with the clutch member 14, and rotated in the direction indicated by the arrows in Figs. 1 and 3. When the starting of the engine is effected and the shaft is being driven in the aforesaid direction, the inclined portions of the teeth 17 will ride over the teeth 18 and

force the clutch member 16 away from the clutch member 14. With the gear and segment of the proportions shown, the clutch member 16 will be given about three quarters of a rotation, or an angular movement of about 270° , as previously mentioned, by one complete swing of the segment 33. This amount of rotation is sufficient, usually, to effect the starting of the engine, if the piston 10 is in the act of making a compression stroke with the charge slightly compressed, when the arm 37 is in normal position. If these conditions do not exist at the time the operator starts the depression of the arm, he may depress the arm until he feels that compression has started, after which he may allow the arm and the driving clutch member 16 to return to normal position. Now, with the compression actually started and the arm in elevated position, he may kick the arm downward the full length of its stroke and impart to the crank shaft the full three-fourths rotation. During this preliminary operation of setting the parts in proper position for the full stroke, it is very important that, immediately upon the start of the backward rotation of the clutch member 16, said clutch member be disengaged from the member 14, in order that no backward movement of the latter clutch member be effected. Such disengagement is assured by the inclination of the teeth of the gear and segment. Furthermore, should the engine fail to start upon the first three-fourths rotation of the crank shaft which is effected by the first complete depression of the arm 37, as many successive actuations of the arm may be made, in rapid succession, as is found necessary to effect such starting. Should the engine "back fire", as previously explained, the clutch member 14 will be given a violent turn in the direction opposite to that indicated by the arrows in the drawing, and will carry the clutch member 16 with it, until the inclined face of its lug 21 engages the inclined face of the projection 44, and the coöperation of the lug and projection will cause a positive rearward pull upon the member 16 and remove its clutch face entirely from the clutch face of the member 14. From this it will be seen that no damage can be caused through the "back-firing" of the engine either to the mechanism or the operator.

Referring again to the spring pressed plungers 24, it will be remembered that they are in frictional contact with the rear face of the clutch member 16. Therefore, besides tending to slide the clutch member 16 toward the clutch member 14 as previously described, they also act to retard its rotation, whereby the inclined teeth of the gear 19 and the segment 33 are rendered more effective in first sliding the clutch member 16 into engagement with the clutch member

14 before any appreciable amount of rotation of the former has occurred.

Having thus described our invention, what we claim is:—

1. In mechanism of the character set forth, the combination, with a member to be rotated, of a clutch member carried thereby, a second clutch member which is rotatable upon substantially the same center as the first clutch member and movable toward and away from the same, said second clutch member having a projection and a circumferential gear, a gear segment for coöperation with the aforesaid gear whereby the second clutch member may be rotated, means tending to move the second clutch member into engagement with the first clutch member, and a device which is adapted to coöperate with the aforesaid projection for moving the second clutch member out of engagement with the first when its direction of rotation is reversed.

2. In mechanism of the character set forth, the combination, with a member to be rotated, of a clutch member carried thereby, a second clutch member which is rotatable upon substantially the same center as the first clutch member and movable toward and away from the same, said second clutch member having a projection and a circumferential angle gear, a device for coöperation with the projection which, when the second clutch member is rotated to cause its projection to engage said device, will move said second clutch member away from the first, and an angle gear segment for coöperation with the aforesaid gear whereby said gear may be rotated in one direction and moved into engagement with the first mentioned clutch member.

3. In mechanism of the character set forth, the combination, with a member to be rotated, of a clutch member carried thereby, a second clutch member which is rotatable upon substantially the same center as the first clutch member and movable toward and away from the same, said second clutch member having a projection and a circumferential gear, a device which is arranged to be engaged by the aforesaid projection when the second mentioned clutch member is rotated in one direction, the projection having an inclined face for engagement with the device, means tending to move the second mentioned clutch member toward the first, and a gear segment for coöperation with the aforesaid gear whereby the second clutch member may be oscillated.

4. In mechanism of the character set forth, the combination, with a member to be rotated, of a clutch member carried thereby, a second clutch member which is rotatable upon substantially the same center as the first clutch member and movable toward and away from the same, said second clutch

member having a projection and a circumferential angle gear, a device for coöperation with the projection which, when the second clutch member is rotated to cause its 5 projection to engage said device, will move said second clutch member away from the first, an angle gear segment for coöperation with the aforesaid gear whereby said gear may be rotated in one direction and moved 10 into engagement with the first mentioned clutch member, means for rocking the segment, and further means tending to rotate the gear in the direction to bring its projection into engagement with the aforesaid 15 device.

5. In mechanism of the character set forth, the combination, with a member to be rotated, of a clutch member carried thereby, a second clutch member which is rotatable 20 upon substantially the same center as the first clutch member and movable toward and away from the same, said second clutch member having a circumferential angle gear, means for retarding the rotation of 25 the second clutch member, and an angle gear segment coöperating with the aforesaid gear.

6. In mechanism of the character set forth, the combination, with a member to be rotated, of a clutch member carried thereby, a second clutch member which is rotatable 30 upon substantially the same center as the first clutch member and movable toward and away from the same, said second clutch member having a circumferential angle gear, means for retarding the rotation of 35 the second clutch member, and means coöperating with said gear for rotating the second clutch member and moving it toward the first.

40 7. In mechanism of the character set

forth, the combination, with a member to be rotated, of a clutch member carried thereby, a second clutch member which is rotatable upon substantially the same center as the first clutch member and movable toward and 45 away from the same, said second clutch member having a projection and a circumferential gear, a device which is arranged to be engaged by the aforesaid projection when the second mentioned clutch member is rotated in one direction, the device having an inclined face for engagement by the projection, means tending to move the second clutch member toward the first, and a gear segment for coöperation with the aforesaid 50 gear whereby the second clutch member may be oscillated.

8. In mechanism of the character set forth, the combination, with a member to be rotated, of a clutch member carried thereby, a second clutch member rotatable upon substantially the same center as the first and movable toward and away from the same, said second clutch member having a projection, means for oscillating said second 55 clutch member, further means for moving the second clutch member toward the first when rotated in one direction, and a device for coöperation with the aforesaid projection which, when the second clutch member 60 is rotated in the opposite direction, will cause a separation of the clutch members.

In testimony whereof, we hereunto affix our signatures in the presence of two witnesses.
